UNITED STATES PATENT OFFICE.

ARTHUR J. RAY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed October 15, 1920, Serial No. 417,146. Renewed October 1, 1925.

To all whom it may concern:

Be it known that I, ARTHUR J. RAY, a citizen of the United States of America, and a resident of Chicago, Cook County, 5 and State of Illinois, have invented certain new and useful Improvements in Automatic Telephone Systems, of which the following is a specification.

This invention relates in general to automatic telephone systems in which connections are established through the medium of subscriber controlled automatic switches, although certain features of the invention appertain more especially to systems of the 10 above character which include one or more manual offices or exchanges, while other features have to do more with small automatic systems of the type commonly known as private automatic exchanges; and the object 15 of the invention is in general to provide a new and improved circuit arrangement for use in telephone systems of the character named.

Considered more in detail, the principal 20 objects accomplished by the invention are the provision of improved circuits for controlling the supervision and disconnection between a manual office and an automatic office, or between two automatic offices; the provision of improved trunking arrangements for handling incoming calls to a private 25 automatic exchange; and the provision of an improved automatic switch for use in private automatic exchanges, the switch being of the type which is commonly known as a selector connector.

The foregoing and other improvements 30 will be described fully hereinafter, reference being had to the accompanying drawings.

Although as stated, the various improvements, or some of them at least, are susceptible of use in several different kinds of systems, it has been chosen to illustrate the 35 invention in connection with a system which includes a public manual office or exchange and a private automatic exchange connected therewith by trunk lines, since this arrangement affords an opportunity to describe the various features to good advantage. In the drawings, comprising Figs. 1, 2, and 3, there is shown by means of the usual circuit diagrams sufficient of the apparatus in the sys-

tem to enable the invention to be explained and understood.

Referring to Fig. 1, the equipment shown is all in the manual exchange. The reference character A indicates a manual substation of the usual type and having the usual line equipment at the exchange. One 55 of the operators' cord circuits is indicated by reference character O. At the right of the sheet is shown a trunk line comprising conductors 40 and 41 which extends to the distant private automatic exchange. 60 This trunk line is provided at the manual office with a repeating coil R and with a group of relays which are indicated by the reference character D. The trunk line also has associated with it the jack J', 65 the line lamp L', and a key K', the latter being provided for the purpose of connecting the calling device S in the circuit when it is desired to call over the trunk line. In Fig. 2 the trunk line mentioned terminates 70 in another repeating coil R' and associated repeater, the latter comprising a group of relays which are indicated by reference character E. At the outgoing side of the repeater E a three conductor trunk line comprising conductors 90, 91, and 92, extends 75 to the rotary line switch C, which has access to the local selector connectors in the private automatic exchange.

One of these last mentioned switches is 80 shown in Fig. 3 where it is indicated by the reference character H. The switch H is a vertical and rotary switch of the well known Strowger type so far as its mechanical construction is concerned and is of course operated according to the two wire system of control. The circuits of the connector have been improved somewhat, however, as will appear more clearly hereinafter.

There may be altogether ninety lines in 85 the private automatic exchange, and these lines may be reached by way of the first nine levels in the selector connectors. One of the lines is the line extending to the substation A', shown at the upper right hand corner 100 of Fig. 3. Substation A' is an automatic substation having the usual ringer, transmitter, and receiver, and a calling devices S' for controlling the automatic switches. The line of substation A' terminates in the first 105 level of the selector connector H and asso-

ciated connectors, as shown, and is provided with an individual rotary line switch C' for handling outgoing calls. The line switch C' in common with the other similar line switches which are associated with the other local lines have access to trunk lines which extend to the selector connectors. One of these trunk lines is the three conductor trunk line comprising conductors 107, 108, and 109, which extend to and terminate in the selector connector H. It will be seen then that the line switches and the selector connectors afford means for setting up local connections within the private automatic exchange.

In order to take care of outgoing calls from the private automatic exchange to the manual office the selector connectors are given access to the interconnecting trunk lines one of which is the trunk line comprising conductors 40, and 41, shown in Fig. 2. This arrangement is shown clearly in the drawings in which conductors 42, 43, and 44 extend from bank contacts 190, 191, and 192, respectively, in the tenth level of the selector connector H, Fig. 3, to the repeater E in Fig. 2. From this it will be evident that the trunk lines connecting the manual offices with the private automatic exchange are two way trunk lines and may be used not only for incoming calls to the private automatic exchange but also for outgoing calls as well.

Having described the apparatus involved, the operation of the same will now be explained more in detail with a view to pointing out the new features. For this purpose it will be assumed that the subscriber at substation A, Fig. 1, desires to establish a connection with the subscriber at substation A', Fig. 3. When the receiver is removed at substation A a circuit is closed over the line for the line relay 2, which attracts its armature and lights the line lamp L in the usual manner. This operation signals the operator at whose position the answering jack J appears, and she will respond to the call by inserting the answering plug of an idle cord circuit, cord circuit O for example, in the answering jack J. When the plug is inserted in the jack the cut off relay 3 is energized, the circuit of the line relay 2 is broken, and the line lamp L is extinguished. At the same time a circuit is completed over the sleeve of the cord for answering supervisory lamp L', but since the receiver is off the hook at substation A the supervisory relay 10 will at once pull up and shunt out the lamp L' to prevent it from lighting at the present time. The operator may now throw her key K to listening position in order to answer the calling subscriber and ascertain what number he wants. Having found that the desired party is the subscriber at substation A' in the distant private automatic exchange the operator will test the

jacks associated with the trunk lines extending to such exchange with the tip of the calling plug in the usual manner, and will insert the plug in the first idle jack. Assuming that the trunk line shown in the drawing is the first idle trunk line, the calling plug will be inserted in the jack J' and a circuit is thereby established for relay 27 which is bridged across the trunk conductors 20 and 22 in series with the left hand windings of the repeating coil R. Upon energizing, relay 27 closes a circuit for the sleeve relay 24 at armature 34 and the said sleeve relay is accordingly energized and establishes a locking circuit for itself at armature 28. The sleeve relay 24 also closes an operating circuit extending to the distant private automatic exchange as follows: From the live pole of the battery by way of the upper winding of relay 26, normally closed contact springs of key K', working contact of armature 29 and the said armature, conductor 21, right hand windings of the repeating coil R in parallel, conductors 40 and 41 in parallel, left hand windings of the repeating coil R' in parallel, conductor 86, armature 70 and its resting contact, armature 82 and its resting contact, and the upper winding of the line relay 56 of the repeater E to ground. Upon the closure of the above circuit relays 26 and 56 are energized in series, and the former relay breaks the circuit of relay 27 at its armature 32. This operation of course opens the circuit of the supervisory relay 11 in the cord circuit also and the lamp L², which is in series with the sleeve relay 24 is lighted.

In the repeater E, when the line relay 56 pulls up it closes a circuit at its armature 78 for the slow acting release relay 55. Upon energizing, the latter relay prepares a circuit for the slow acting relay 54 at its armature 74, and at its armature 75 connects ground to the release trunk conductor 43, thus placing a ground potential upon the multiple test contacts in which this release trunk conductor terminates in the banks of the selector connectors. This makes the trunk line busy to outgoing calls from the private automatic exchange. In addition to the foregoing, relay 55 also closes a bridge across the trunk conductors 90 and 92 by means of its armature 76. This bridge may be traced from conductor 90 by way of the working contact of armature 77 and the said armature (line relay 56 being now energized), conductor 42, right hand winding of repeating coil R', armature 60 and its resting contact, retard coil 85, upper winding of the electropolarized relay 59, resting contact of armature 61 and the said armature, lower right hand winding of the repeating coil R', conductor 44, armature 76 and its working contact, and resting contact of armature 63 and the said armature 130

to conductor 92. When the above bridge is closed the upper winding of relay 59 is bridged across conductors 90 and 92 in series with the retard coil 85 and a circuit is thus closed for the line relay 93 of the line switch C. Upon energizing, the line relay 93 closes a circuit at its lower armature for the switching relay 98 in series with the stepping magnet 94, and at its upper armature connects the test wiper 96 to the above circuit at a point midway between the said relay and magnet. The connection of the test wiper to the junction of the switching relay and stepping magnet is to provide for rotating the switch in search of an idle trunk line in case the trunk line with which the wipers are already associated is busy. We may assume, however, that the trunk line shown in the drawing and comprising conductors 104, 105, and 106, which terminate in the bank contacts 101, 102, and 103, respectively, upon which the wipers of the line switch are now standing, is idle, and it follows therefore that when the line relay 93 is energized as described, no rotation of the switch will take place, for the test wiper 96 will find no ground potential upon test contact 102; but instead, the switching relay 98 will be energized immediately, and at its middle armature will connect ground to the test wiper 96 in order to busy the trunk. The switching relay 98 having energized, the trunk conductors 90 and 92 are now extended by way of the upper and lower armatures of the said switching relay, wipers 95 and 97, bank contacts 101 and 103, conductors 104 and 106, normally closed contacts controlled by armatures 136 and 139, normally closed contacts of the reversing relay 121, and the windings of the double wound line relay 122 to battery and ground, respectively. Since there is a bridge across the conductors 90 and 92 at the repeater E, as previously described, the line relay 122 is now energized and closes a circuit for the slow acting release relay 123. Upon energizing, the latter relay prepares a circuit for the vertical magnet 129 at armature 141 and at armature 145 connects ground to the release trunk conductor 105. By the latter operation a holding circuit is completed in the usual manner for the switching relay 98 of the line switch C. Ground is also extended by way of conductor 108 to test contact 111 and its multiples in the banks of the line switches, thereby making the selector connector H busy to all the local line switches as well as to those line switches such as the line switch C which are associated with the incoming trunk lines.

It should be mentioned before proceeding that the electropolarized relay 59 in the repeater E is not operated when the same is connected in series with the line relay 93 of

the line switch C or the line relay 122 of the connector H. This is because of the effect of the lower polarizing winding of the relay which is supplied with current from the release trunk conductor 43. The two windings of relay 59 are opposed to each other under the conditions described and the relay therefore remains inoperative as stated.

The foregoing operations have all taken place automatically in response to the insertion of the plug in jack J'. The operator will now throw the key K' in order to connect the calling device S in the control circuit, and will then proceed to call the digits in the number of the subscriber at substation A'. When key K' is operated it will be seen that the calling device S is substituted for the upper winding of relay 26 in the previously described circuit of the line relay 56 at the repeater E, and at the same time a circuit is closed through the lower winding of relay 26 in order to hold this relay up while the calling device dial is being operated. When the calling device is operated for the first digit a series of interruptions is produced in the circuit of the line relay 56, this line relay is deenergized a plurality of times, and the bridge across the trunk conductors 90 and 92 is accordingly broken a plurality of times. The line relay 56 also sends a plurality of impulses to the slow acting relay 54, the circuit including the armature 78 and its resting contact, and relay 54 is accordingly energized and held up during the series of impulses. At its armature 71 relay 54 closes the bridge across conductors 90 and 92 over a direct path which includes only the armature 77 of the line relay 56, armature 71 and its working contact, and the resting contact of armature 63 and the said armature. This is the same arrangement as is usually employed in all repeaters in order to secure an efficient switch control circuit on the outgoing side of the repeater.

We may now pass on to the connector H and consider its operation in response to impulses. When the bridge across conductors 90 and 92 is broken a plurality of times by the line relay 56 as just described, the line relay 122 of the connector H responds by deenergizing a like number of times, and at the first deenergization an impulse is transmitted to the vertical magnet 129 over the following circuit: Ground at G³, armature 138 and its resting contact, armature 140 and its resting contact, armature 141 and its working contact, off normal springs 144 and 142, winding of the slow acting series relay 124, and the winding of the vertical magnet 129 to battery. Upon the first vertical movement of the switch the off normal springs are shifted, and the remaining impulses to the vertical magnet traverse a new circuit which is the same as the one previously

traced except that it includes the off normal springs 144 and 143, and armature 148 and its working contact, the slow-acting relay 124 being now in operated position. By the 5 operation of the vertical magnet 129 the switch wipers 170, 171, and 172, are raised step by step and are finally brought to rest opposite the level in which the line of substation A' is terminated. In case the line of 10 substation A' is terminated in the first level, the first digit in the local number will be the digit 1, only one impulse of current will be transmitted to the vertical magnet, instead of a plurality of impulses as described 15 in the foregoing, and the switch wipers will be raised opposite the first level. The slow acting series relay 124 is energized in series with the vertical magnet and retains its armatures in attracted position while all the 20 impulses corresponding to the first digit in the number are being received. Its function at this time is to maintain the vertical magnet circuit intact by means of its armature 148, notwithstanding the shifting of the off 25 normal springs at the first upward movement of the shaft. At the end of the vertical movement of the switch relay 124 is deenergized and transfers the operating circuit to the rotary magnet 131.

30 The operator may now call the next and last digit in the desired number. As before, a series of interruptions are produced in the control circuit of the line relay 56, which are repeated by the said relay into the 35 circuit of the line relay 122 of the connector H. In response to the second series of interruptions the line relay 122 is deenergized a plurality of times as before and sends a series of impulses to the rotary magnet 131 40 as follows: Ground at G³, armature 138 and its resting contact, armature 140 and its resting contact, armature 141 and its working contact, off normal springs 144 and 143, armature 148 and its resting contact, winding 45 of the slow acting series relay 127, resting contact of armature 162 and the said armature, and the winding of the rotary magnet 131 to battery. By the operation of the rotary magnet 131 the switch wipers are 50 rotated step by step and are finally brought to rest in engagement with the particular set of contacts in which the line of substation A' is terminated, these contacts being indicated in the drawing by reference characters 173, 174, and 175. The slow acting 55 relay 127 is energized in series with the rotary magnet and maintains its armatures attracted throughout the rotary movement. At its armature 157 relay 127 connects the 60 test wiper 171 to the winding of the test relay 126, and at its armature 158 places a shunt around the break contacts controlled by armature 155 of the said test relay. The latter operation is to guard against the 65 possibility of the rotary magnet circuit being

broken by the operation of the test relay while the test wiper is passing over busy test contacts.

It will be assumed now that the line of substation A' is busy when called. Under 70 these circumstances there will be a ground potential upon the test contact 174 and when the test wiper 171 comes to rest in engagement therewith the test relay 126 will be 75 energized. The test relay locks itself at its armature 154 in an obvious manner, breaks the rotary magnet circuit at its armature 155, and at its armature 156 connects a lead from the busy signalling machine to the lower heavy talking conductor, thereby 80 transmitting an audible busy signal to the operator and to the calling subscriber. This is the usual busy signal employed in automatic systems and its function will be understood without further explanation. 85

Having explained what occurs when the desired called line is busy, it will now be assumed that the called line is idle. Such being the case, when the test wiper 171 comes to rest in engagement with test contact 174, 90 it will find no ground potential and the test relay 126 will not be energized. Instead, when the slow acting relay 127 falls back, a circuit is closed through the lower winding 95 of the switching relay 128 as follows: From the grounded release trunk conductor 105, by way of armature 154 and its resting contact, lower winding of relay 128, resting contact of armature 157 and the said armature, test wiper 171, test contact 174, winding of the switching relay 180 of the line switch C', and the winding of the stepping magnet 182 100 to battery. Upon the closure of the above circuit relays 128 and 180 are energized in series, and the latter relay is operated to 105 clear the line of substation A' from its normal battery and ground connections in the line switch C'. It is noted that due to a mechanical interlocking device controlled by the armature of the line relay 181, relay 180 110 is operated only about half way and the wipers of the line switch are not connected up. In the connector H, when the switching relay 128 is energized it closes a locking circuit for itself at its armature 160, grounds 115 the test wiper 171 at armature 161, breaks the operating circuit for the rotary magnet 131 at armature 162, and at armature 166 connects up the lower line wiper 172. It is 120 noted that the usual pair of contact springs for connecting up the upper wiper 170 is omitted and this function is taken care of by a make contact on armature 162 whereby the upper winding of the ring cut off relay 125 is connected to battery through the low 125 resistance rotary magnet 131.

The connection to the desired called line has now been completed and ringing current from the generator Gen is intermittently projected out over the line to operate the 130

bridged ringer at substation A'. The ringing circuit is of the usual character and need not be described in detail. When the called subscriber responds by removing his receiver from the hook the ring cut off relay 125, whose upper winding is included in the return path of the ringing current, is operated and establishes a locking circuit for itself at its armature 151. Relay 125 also breaks the ringing circuit at the resting contacts of its armatures 150 and 152, and at the working contacts of these same armatures finally completes the talking circuit. The transmitter at substation A' is now supplied with talking current through the windings of the double wound back bridge relay 121, and this relay is accordingly energized, with the result that incoming trunk conductors 104 and 106 are reversed as regards their connection to the windings of the line relay 122. It follows that the direction of current flow in the trunk line and in the bridge at the repeater E is reversed and the electropolarized relay 59 at the said repeater, whose upper winding is included in the bridge and which until now has remained inoperative, is at once energized by the combined effect of its two windings. Upon attracting its armature 84 relay 59 closes a circuit through the lower winding of the line relay 56 and at the same time completes a circuit through the lower winding of the relay 58. Upon energizing, relay 58 disconnects the conductor 86 in the control circuit coming from the distant manual exchange from the upper winding of the line relay 56 and connects it instead to the upper winding of relay 57, relay 56 being now held energized by the circuit through its lower winding.

The control circuit has now been switched from ground to the live pole of battery at repeater E and the effect of this operation at the manual exchange will now be considered. Assuming that the operator has already restored her key K', which will ordinarily be the case, until the called subscriber answered his telephone the control circuit was connected to the live pole of battery at the manual exchange through the upper winding of relay 26 and this relay was held up in series with the line relay 56 at the repeater E. Now, however, since the other end of the control circuit has been switched from ground to battery no current will flow over the control circuit, relay 26 will fall back, and relay 27 will again be bridged across the conductors 20 and 22 in series with the left hand windings of the repeating coil R. As a result, the supervisory relay 11 in the cord circuit is energized, and the supervisory lamp L² is extinguished to notify the operator that the called party has answered. Conversation between the two subscribers may now take place in the ordinary manner, as

will be understood without further consideration. 65

The manner in which the connection is released depends upon whether the called subscriber hangs up before or after the operator pulls down the connection. Ordinarily when the subscribers are through talking they will both hang up their receivers at once. The replacement of the receiver at substation A of course lights the supervisory lamp L' by the deenergization of the supervisory relay 10. When the receiver is replaced at substation A' the back bridge relay 121 will fall back and reverse the direction of current flow in the trunk line incoming to the connector H and in the bridge across said trunk line at the repeater E to normal. The two windings of relay 59 now oppose each other, the said relay retracts its armature, and the circuits through the lower windings of relays 56 and 58 are broken. The latter relay upon deenergizing, disconnects the control circuit from the upper winding of relay 57 and connects it back to the upper winding of the line relay 56 as before. The control circuit is now in the same condition as when originally established and relay 26 will again be energized, thereby removing the relay 27 from in bridge of conductors 20 and 22 in order to deenergize the supervisory relay 11 and light the supervisory lamp L^2 . When the operator perceives the disconnect signals she will pull down the connection. When the plug is removed from jack J' the circuit of the sleeve relay 24 is broken and the conductor 21 in the control circuit is disconnected from the upper winding of relay 26 and is connected instead to the winding of relay 25, and thence to ground, this being the normal condition of the circuit. The line relay 56 at repeater E will now fall back and break the circuit of the slow acting relay 55, at the same time opening the bridge across conductors 90 and 92 at armature 77. Upon deenergizing, relay 55 disconnects ground from the release trunk conductor 43 and thus removes the busy condition from the test contact 191 and its multiples in the banks of the selector connectors. When the bridge across the trunk line is broken at armature 77 the line and release relays 122 and 123 of the connector H are deenergized and the latter relay disconnects ground from the locking circuits of relays 125 and 128 thereby deenergizing these relays. At the same time relays 122 and 123 jointly close a circuit for the release magnet 130 through the medium of which the connector H is restored to normal condition in the usual manner.

If the subscriber at substation A is the only one who hangs up his receiver and the operator should desire to release the con-

nection she can do so even if the receiver at substation A' is left off the hook. This operation will now be briefly explained, it being assumed that the operator wishes to release the connection before the subscriber at substation A' has hung up his receiver. When the plug is removed from the jack J', the sleeve relay 24 is deenergized and the conductor 21 in the control circuit is connected to ground through the winding of relay 25 as described. In the repeater E the conductor 86 in the other end of the control circuit now extends through the upper winding of relay 57 to battery and the latter relay is accordingly energized. Upon operating, relay 57 closes a circuit from the release trunk conductor 91 by way of armature 79 and its working contact to the upper winding of relay 58, and breaks the circuit of the lower winding of the line relay 56 at armature 80. The line relay 56 is accordingly deenergized, breaks the circuit of the slow acting release relay 55, and also interrupts the bridge across the trunk conductors 90 and 92 at armature 77. When the bridge is opened at armature 77 the release of the connector H is initiated and the electro-polarized relay 59, which is included in the bridge, falls back, for this relay is so adjusted that the current flow through the polarizing winding will not hold it in operated position. Relay 58, however, does not deenergize at this time due to the fact that it is locked to the release trunk conductor 91. When the relay 55 deenergizes ground is not removed from the release trunk conductors 43 at once, but this conductor remains grounded at armature 83 of relay 58. When the line and release relays 122 and 123 of the connector H fall back the connector is released in the usual manner and ground is disconnected from the release trunk conductor 105. The switching relay 98 of the line switch C now falls back, and at the same time relay 58 in the repeater E is deenergized. The latter operation finally clears the release trunk conductor 43 of ground, after all the equipment in use has been restored to normal, and the trunk line is made accessible for outgoing calls. The control circuit is also shifted back into connection with the upper winding of relay 56 and relay 57 is permitted to deenergize. Both ends of the control circuit are now connected to ground and the current flow therein will cease. It is noted that when the operator releases the connection under the conditions just described, when the called subscriber has not yet hung up his receiver, the relay 25 in the manual exchange is energized for a short interval in series with the upper winding of relay 57 at the repeater E. This lights the line lamp L³ for a brief instant which indicates to the operator that the circuits are working properly.

When the line lamp goes out the operator will know that the connection has been released.

Having described the process of setting up a connection from the manual exchange to the private automatic exchange the process of setting up a connection in the opposite direction between the same exchanges will now be explained briefly and for this purpose it will be assumed that the subscriber at substation A' desires a connection with the subscriber at substation A. When the receiver is removed at substation A' a circuit is closed over the line conductors 176 and 178 for the line relay 181 of the individual line switch C'. Upon energizing, relay 181 closes a circuit at its lower armature which includes the winding of the switching relay 180 and the winding of the stepping magnet 182 in series, while at the same time by means of its upper armature the test wiper 184 is connected to the above circuit at a point midway between the said switching relay and stepping magnet. This latter operation is to provide for automatic rotary movement in search of an idle trunk line, as was described in the case of the line switch C, Fig. 2, but in the present case we may assume that the wipers 183-185, inclusive, of the line switch are resting in engagement with bank contacts 110-112, inclusive, when the call is initiated, and the trunk line extending to the connector H which terminates in this contact set is id'e. Under these circumstances no rotation of the switch will take place, for the test contact 111 will not be grounded, and the switching relay 180 will pull up immediately when its circuit is closed by the operation of the line relay 181. Upon energizing, the switching relay 180 connects the grounded conductor 177 to the test wiper 184 by means of its inner armature and by means of its two outer armatures disconnects the line conductors 176 and 178 from the line relay 181 and ground, respectively, and extends them by way of wipers 183 and 185, bank contacts 110 and 112, conductors 107 and 109, conductors 104 and 106, normally closed contact springs controlled by armatures 136 and 139, normally closed contacts of the reversing relay 121, and the upper and lower windings of the relay 122 to battery and ground, respectively.

When the calling line is extended to the connector H as above described the line and release relays 122 and 123 are energized in the usual manner. The latter relay prepares a circuit to the vertical magnet at its armature 141, and its armature 145 connects ground to the release trunk conductor 105, thereby establishing a holding circuit for the line switch C' which may be traced by way of the said conductor 105, conductor 108, test contact 111, test wiper 184, middle

armature of relay 180 and its working contact, winding of relay 180, and the winding of the stepping magnet 182 to battery. The above circuit serves to maintain the switching relay 180 in energized position throughout the connection.

It will be seen that the selector connector H has been taken for use responsive to the removal of the receiver at substation A' and it follows therefore that everything is ready for the calling subscriber to operate his calling device to select and connect with an idle trunk line extending to the manual exchange. As hereinbefore stated, these trunk lines are 15 terminated in the tenth level of the selector connectors and it will be necessary then to operate the calling device in accordance with the digit 0. When the calling device is operated for this digit a series of ten interruptions is produced in the circuit of the line relay 122, and as a result this relay responds by sending ten impulses to the vertical magnet 129. The selector connector H is operated in its vertical movement the 20 same as has been already described and the wipers are raised step by step until they come to rest opposite the tenth level. The slow acting series relay is of course energized in series with the vertical magnet and 25 performs the same functions that it did before. In addition certain circuit changes are produced at the upper armature 147 of relay 124 which in the former case were ineffective. Before considering these circuits, 30 however, the operation of the shaft springs 132, 133, 134, and 135 must be considered. These springs are intended to be shifted only when the shaft is raised to the tenth level and for this purpose are preferably 35 mounted on the switch frame in such a position that the left hand spring 132 may be engaged by the circular cup spring casing when the shaft is raised to the proper level. Springs 132 and 134 may thus be forced into 40 engagement, respectively, with springs 133 and 135. Since in the present case the switch shaft has been raised to the tenth level the shaft springs will be shifted as 45 stated and by the closure of springs 132 and 133 the winding of the switching through relay 120 is connected in parallel with the locking winding of the switching relay 128. By the closure of the shaft springs 134 and 135 a circuit is completed which extends 50 from the grounded release trunk conductor 105 by way of the springs mentioned, armature 147 and its working contact (relay 124 being now in operated position), interrupter contact 153 of the rotary magnet 131 and 55 the winding of the test relay 126 to battery. The test relay 126 is energized over the 60 above circuit, locks itself at its armature 154, and at its armature 155 prepares a circuit for the rotary magnet 131. An instant 65 later at the completion of the vertical move-

ment of the switch the slow acting relay 124 is deenergized and at the resting contact of its armature 147 closes a circuit for the rotary magnet 131 which may be traced without difficulty. The rotary magnet is accordingly energized and rotates the switch wipers 170-172, inclusive, into engagement with the first set of bank contacts in the tenth level. In operating the rotary magnet breaks the locking circuit of the test relay 126 at its interrupter contact 153 and the said test relay therefore falls back and breaks the rotary magnet circuit at armature 155, whereupon the rotary magnet will be energized also. However, the slow acting series relay 127 has been energized in series with the rotary magnet 131 and the test wiper 171 therefore is now connected to the winding of the test relay 126. It follows therefore that if the test contact with which 75 the test wiper 171 is now in engagement is busy the test relay 126 will again be energized and the rotary magnet 131 will again be operated to advance the switch wipers into engagement with the next set of bank 80 contacts, this operation being repeated as many times as is necessary. Assuming that the trunk line shown in the drawing is the first idle trunk line, this being the trunk line which terminates in the contact set comprising bank contacts 190, 191, and 192, when the test wiper 171 arrives at test contact 191 it will find no ground potential, and the test relay 126 will not again be energized. The rotation of the switch will therefore cease 85 and when the slow acting series relay 127 falls back an instant later a circuit is completed for the lower winding of the switching relay 128 as follows: From the grounded release trunk conductor 105 by way of 90 armature 154 and its resting contact, normally closed contact springs controlled by armature 163, lower winding of the switching relay 128, resting contact of armature 157 and the said armature, test wiper 171, 95 test contact 191, conductor 43, armature 75 and its resting contact, armature 83 and its resting contact, and the winding of relay 50 to battery. Relays 128 and 50 are energized in series over the above circuit and the 100 former relay closes a circuit for its locking winding and the winding of relay 120 in parallel at armature 160. Other circuit changes produced by the energization of relay 128 have been already described and need 105 not again be considered in detail. When the switching through relay 120 is energized it disconnects ground from the armature 140 of the line relay 122 by means of armature 138, disconnects armature 161 of the switching 110 relay from direct ground and connects said armature instead to armature 146 of relay 123, this circuit change being accomplished at armature 137, while at armatures 136 and 139 the incoming trunk conductors 104 and 115 120 125 130 135 140 145 150 155 160 165 170 175 180 185 190 195 200

106 are connected direct to the line wipers 170 and 172, all bridges and relays in the selector connector H being disconnected at the same time. When the incoming trunk 5 conductors 104 and 106 are connected through in this manner the line and release relays 122 and 123 are of course deenergized, but before the latter relay has time to fall back a holding circuit is established over 10 conductor 43 as will be presently described.

Considering now the operations at the repeater E when the relay 50 is energized in series with the switching relay 128 of the selector connector H, the said relay disconnects the right hand windings of the repeating coil R' from the bridged electropolarized relay 59 and connects these windings instead by way of the contacts of the reversing relay 51 to the upper and lower windings of 20 the double wound line relay 52, these circuit changes being accomplished at armatures 60 and 61.

Relay 50 also closes a circuit for the reversing relay 51 at its armature 62, and at 25 its armature 63 opens the lower heavy talking conductor in the direction of the line switch C. It will be observed now that the trunk conductors 42 and 44 have been extended through to the windings of the line 30 relay 52, and since the calling line has been connected with these trunk conductors by the operation of the selector connector H, as described, the line relay 52 will be energized over the calling line circuit and will 35 close an energizing circuit for the slow acting release relay 53. Upon energizing, the latter relay prepares a circuit for the slow acting relay 54 at its armature 67 and at its armature 68 closes a holding circuit extending 40 back to the selector connector H as follows: From ground at G³, by way of armature 68 and its working contact, armature 62 and its working contact (a branch extends from this point through the winding 45 of relay 50 to battery), resting contact of armature 83 and the said armature, resting contact of armature 75 and the said armature, conductor 43, test contact 191, test wiper 171, armature 157 and its resting contact, armature 163 and its working contact, 50 and the resting contact of armature 154 and the said armature to the release trunk conductor 105, where it joins the previously described holding circuit extending by way 55 of conductors 105 and 108 to the line switch C'. A branch of the circuit just described extends from the test wiper 171 by way of the working contact of armature 161 and the said armature, armature 137 and its working 60 contact, and thence by way of the locking windings of relays 125 and 128 and the winding of relay 120 to battery. The holding circuit described therefore serves to maintain the relays in the selector connector 65 which have been named energized until the

connection is released, as well as the switching relay 180 of the line switch C'.

Returning now to the repeater E, when the slow acting relay 52 attracts its armature 70 it disconnects the conductor 86 in the control circuit from the upper winding of the line relay 56 and connects it instead by way of the working contact of armature 70, armature 69 and its working contact, and the lower winding of relay 57 to battery. 75 Since the other end of the control circuit normally extends through the winding of the relay 25 at the distant manual exchange to ground, relays 25 and 57 will now be energized in series, and the latter relay at its armature 81 breaks the circuit of the reversing relay 51. It will be recollected that the circuit of relay 51 was closed an instant before at armature 62 of relay 50, but relay 51 has a very stiff adjustment and its operation is thus delayed sufficiently so that its circuit is broken by relay 57 before it has time to attract its armature far enough to reverse the trunk conductors. At the manual exchange when the relay 25 is energized 80 it closes a circuit for the lamp L³, and the operator is thus notified that a call has been received over the associated trunk line. The call is answered by plugging into the jack J', as will be readily understood, and when 85 this is done relays 27 and 24 are energized, the latter relay being operated over the sleeve of the cord as soon as its circuit is closed by relay 27. Upon energizing, relay 24 disconnects conductor 21 in the control 90 circuit from ground through the winding of relay 25 and connects it instead by way of the upper winding of relay 26 to battery. Both ends of the control circuit are now connected to the same pole of the respective 95 exchange batteries and relay 57 in the repeater E is accordingly deenergized. When relay 57 falls back it closes a circuit for the reversing relay 51 at its armature 81 and the reversing relay is therefore operated to 100 reverse the trunk conductors 42 and 44 as regards their connection to the windings of the line relay 52. This reverses the direction 105 of current flow in the calling line, and is a standard operation commonly used in automatic telephone systems, the purpose being 110 to provide for controlling a subscriber's meter or coin collecting device. There is nothing new in this operation, however, and no such devices have been shown in connection 115 with the line of substation A', but it is customary to include this reversing feature in the central office switches whether it is used or not.

The operator will now throw her key K 120 to listening position, and having found that the desired party is the party at substation A, she will complete the connection with the other end of her cord circuit in the usual manner. These operations will be 125

understood without difficulty, but it may be advisable to consider briefly the supervisory circuits in this type of connection. The supervisory lamp L' is of course lighted 5 when the operator plugs into the jack of the called line and is extinguished when the called party answers. The supervisory lamp L^2 is not lighted when the operator plugs into the jack J' , because the supervisory relay 11 is energized at once in series with the relay 27. When the subscribers hang up their receivers both supervisory lamps are lighted, lamp L' by the deenergization 10 of the supervisory relay 10 and lamp L^2 by the deenergization of supervisory relay 11. The deenergization of the latter relay is brought about by the release of the connection in the private automatic exchange. When the subscriber at substation A' hangs 15 up his receiver the circuit of the line relay 52 in the repeater E is broken and this relay and the slow acting release relay 53 will retract their armatures. The latter relay upon deenergizing, breaks the holding circuit for the line switch C' and relays 120, 125, and 128, in the selector connector H, and both these switches are accordingly restored to normal position. Relay 53 also disconnects the conductor 86 from the lower 20 winding of relay 57 and connects it back by way of the upper winding of line relay 56 to ground. Since the other end of the control circuit now extends through the upper winding of relay 26 to battery, relays 56 and 26 will be energized in series and relay 26 will operate to disconnect the relay 27 from in bridge of conductors 20 and 22. This breaks the circuit of the supervisory relay 11 and the supervisory lamp 25 L^2 is lighted to give the operator a disconnect signal. It is noted that when the line relay 56 energizes it closes a circuit for the slow acting relay 55 and since relay 50 has now deenergized, the electropolarized relay 59 is connected across the trunk conductors 90 and 92, as in the case when the 30 call was being extended from the manual exchange to a subscriber in the private automatic exchange. Although the line switch C is thus operated to select an idler selector connector, this causes no particular harm, for the operator at the distant manual exchange will pull down the connection as soon as she sees the lighted supervisory lamps 35 and the control circuit will again be connected to ground through the winding of relay 25. This causes relays 56 and 55 at the repeater E to deenergize, and the circuits are thus restored to normal condition. 40

This completes the explanation, but before closing it should perhaps be explained that the trunk circuit shown is especially adapted for use between widely separated exchanges. In view of the fact that the 45 automatic switches are controlled over a

simplex circuit including two sides of the trunk line in parallel, a low resistance control circuit is secured which is very efficient, and automatic switches may be operated successfully over trunk lines of one hundred 50 miles or more in length. However, there is no reason why the circuit shown cannot be used for relatively short trunk lines if desired, and the advantages of especially efficient control circuits are of course secured 55 under these conditions also. It may be stated furthermore, that if the trunk circuit shown is used the manual exchange may be changed to an automatic exchange without 60 in the least altering the trunk circuits at 80 the private automatic exchange. Suppose for example, that the manual exchange contemplated by the present layout is replaced by a modern automatic exchange. When this is done each of the trunk lines extending to the private automatic exchange is provided with a repeater, exactly like the repeater E, in the new automatic exchange, and connections can then be established 65 automatically in both directions. It is noted in this connection that the line relay 52 of the repeater E has an armature 69 which is included in the control circuit established when the trunk line is taken for use by a subscriber in the private automatic exchange, as described in the case where the subscriber at substation A' was calling the subscriber at substation A. In case the other end of the trunk line is terminated in a repeater similar to the repeater E, the 70 other end of this control circuit will extend to ground by way of a line relay similar to the line relay 56 and this line relay may of course be controlled by interruptions 75 in the control circuit produced at armature 69 of the line relay 52 when the calling subscriber in the private automatic exchange operates his calling device. It is believed 80 that the method of operating when repeaters are used on both ends of the trunk line will be sufficiently clear now from what has been said, but to insure a complete disclosure of these matters reference is made to the pending application of John Wicks, Serial No. 239,323, filed October 23, 1918. 85

Having described my invention, what I consider to be new and desire to have protected by Letters Patent will be pointed out in the appended claims.

What I claim as my invention is:

1. In a telephone system, a manual exchange and an automatic exchange, a trunk line terminating in an operator's position at the first exchange and an automatic switch at the second exchange, a repeating coil included in the trunk line at the manual exchange, the trunk line conductors coming from the operator's position being normally conductively connected through two windings of said coil, means whereby the opera- 120

tor can connect with said trunk line and establish a flow of current in a control circuit including the two sides of said trunk line in parallel, means responsive to the current flow for opening said normally connected conductors for lighting a supervisory lamp, means for momentarily interrupting the control circuit, automatic switches at the automatic exchange responsive to the interruptions to connect with a called line, means operated when the called man answers for preventing the flow of current in said control circuit during conversation, and means responsive to the cessation of current flow in said control circuit for again connecting said normally connected conductors to extinguish said lamp.

2. In a telephone system, a manual exchange and an automatic exchange, a trunk line terminating in an operator's position at the first exchange and an automatic switch at the second exchange, a repeating coil included in the trunk line at the manual exchange, the trunk line conductors coming from the operator's position being normally conductively connected through two windings of said coil, means whereby the operator can connect with said trunk line and establish a flow of current in a control circuit including the two sides of said trunk line in parallel, means responsive to the current flow for opening said normally connected conductors for lighting a supervisory lamp, means for momentarily interrupting the control circuit, means for holding said conductors open while interruptions are being produced, automatic switches at the automatic exchange responsive to the interruptions to connect with a called line, means operated when the called man answers for preventing the flow of current in said control circuit during conversation, and means responsive to the cessation of current flow in said control circuit for again connecting said normally connected conductors to extinguish said lamp.

3. In a telephone system, a manual exchange and an automatic exchange, a trunk line terminating in an operator's position at the first exchange and an automatic switch at the second exchange, a repeating coil included in the trunk line at the manual exchange, the trunk line conductors coming from the operator's position being normally conductively connected through two windings of said coil, means whereby the operator can connect with said trunk line and establish a flow of current in a control circuit including the two sides of said trunk line in parallel, means responsive to the current flow for opening said normally connected conductors for lighting a supervisory lamp, means for momentarily interrupting the control circuit, automatic switches at the automatic exchange responsive to the interruptions to connect with a called line, means operated when the called man answers for preventing the flow of current in said control

tions to connect with a called line, means operated when the called man answers for preventing the flow of current in said control circuit during conversation, means responsive to the cessation of current flow in said control circuit for again connecting said normally connected conductors to extinguish said lamp, and means operated when the operator pulls down the connection for re-establishing a current flow in said control circuit to release said switches.

4. In a telephone system, a manual exchange and an automatic exchange, a trunk line terminating in an operator's position at the first exchange and an automatic switch at the second exchange, a repeating coil included in the trunk line at the manual exchange, the trunk line conductors coming from the operator's position being normally conductively connected through two windings of said coils, means whereby the operator can connect with said trunk line and establish a flow of current in a control circuit including the two sides of said trunk line in parallel, means responsive to the current flow for opening said normally connected conductors for lighting a supervisory lamp, means for momentarily interrupting the control circuit, automatic switches at the automatic exchange responsive to the interruptions to connect with a called line, means operated when the called man answers for preventing the flow of current in said control circuit during conversation, means responsive to the cessation of current flow in said control circuit for again connecting said normally connected conductors to extinguish said lamp, means operated when the operator pulls down the connection for reestablishing a current flow in said control circuit to release said switches, and a second supervisory signal operated while the release of said switches is taking place.

5. In a telephone system, a manual exchange and an automatic exchange, a trunk line terminating in an operator's position at the first exchange and an automatic switch at the second exchange, a repeating coil included in the trunk line at the manual exchange, the trunk line conductors coming from the operator's position, being normally conductively connected through two windings of said coil, means whereby the operator can connect with said trunk line and establish a flow of current in a control circuit including the two sides of said trunk line in parallel, means responsive to the current flow for opening said normally connected conductors for lighting a supervisory lamp, means for momentarily interrupting the control circuit, automatic switches at the automatic exchange responsive to the interruptions to connect with a called line, means operated when the called man answers for preventing the flow of current in said control

5 circuit during conversation, means responsive to the cessation of current flow in said control circuit for again connecting said normally connected conductors to extinguish said lamp, means operated when the operator pulls down the connection for reestablishing a current flow in said control circuit to release said switches, a second supervisory lamp lighted during the releasing operation, 10 and means whereby said second lamp is controlled over said control circuit from the automatic exchange and is extinguished when the releasing operation is finished.

6. In a telephone system, a two way trunk 15 line and a lamp signal at one end thereof, means including automatic switches for setting up connections over said trunk line in both directions, and means whereby said lamp is operated as a call signal when connections are extended in one direction and as a release signal when connections are extended in the other direction.

7. In a telephone system, a manual exchange and an automatic exchange, a two 25 way trunk line connecting said exchanges, a lamp signal associated with said trunk line at the manual exchange, means for lighting said lamp when a call is received over said trunk line from the automatic exchange, 30 means for extending a call over said trunk line in the other direction by means of switches in the automatic exchange, and means for lighting said lamp when the switches are released.

35 8. In a telephone system, a main exchange, a private branch exchange, trunk lines extending from the main exchange to the branch exchange and there terminating in line switches, other line switches in which the local lines in the branch exchange terminate, and local connectors which are accessible to the wipers of all said line switches in common.

9. In a telephone system, a main exchange, 45 a private branch exchange, trunk lines connecting said exchanges, local connectors in the branch exchange having access to the local lines and also to the inter-office trunk lines, and line switches associated with the local lines and the trunk lines which have common access through their bank contacts to said connectors.

10. In a telephone system, a trunk line 55 terminating in a combination selector and connector switch, groups of local lines and trunk lines accessible to said switch, a relay for changing the character of said switch from that of a connector to that of a selector when the switch is operated to select a group of trunk lines, a test wiper in said switch for testing either local lines or trunk lines as to their busy or idle condition, means for directly grounding said test wiper when a local line is connected with, and means for con-

necting said test wiper to a third conductor 65 of said first trunk line when another trunk line is connected with.

11. In a telephone system, a trunk line, a normally closed switch control circuit including the two sides of said trunk line in parallel, means at one end of said trunk for establishing a flow of current in said circuit and for thereafter producing interruptions therein, an automatic switch at the other end of said trunk line responsive to said interruptions for connecting with a called line, and means operated upon the response of the called subscriber for closing said circuit over a new path to prevent the flow of current therein during conversation. 80

12. In a telephone system, a trunk line, a normally closed switch control circuit including the two sides of said trunk line in parallel, means at one end of said trunk for establishing a flow of current in said circuit 85 and for thereafter producing interruptions therein, an automatic switch at the other end of said trunk line responsive to said interruptions for connecting with a called line, means operated upon the response of the 90 called subscriber for closing said circuit over a new path to prevent the flow of current therein during conversation, and means responsive to the restoration of said circuit to normal condition at the calling end of the 95 trunk for releasing said switch.

13. In a telephone system, two exchanges and an interconnecting trunk line, means in the first exchange for establishing a current flow over a closed switch control circuit 100 including the two sides of said trunk line in parallel, an automatic switch in the second exchange responsive to interruptions produced in said circuit for extending a connection to a called line, and means operated 105 upon the response of the called subscriber for preventing the flow of current over said closed control circuit during conversation.

14. In a telephone system, two exchanges and an interconnecting trunk line, means in 110 the first exchange for establishing a current flow over a closed switch control circuit including the two sides of said trunk line in parallel, an automatic switch in the second exchange responsive to interruptions produced in said circuit for extending a connection to a called line, means operated upon the response of the called subscriber for preventing the flow of current over said closed control circuit during conversation, the current flow being reestablished when the called subscriber hangs up, and means controlled 115 from the calling end of the trunk line for releasing said switch.

15. In a telephone system, two exchanges and an interconnecting trunk line, means in 125 the first exchange for establishing a current flow over a closed switch control circuit in-

cluding the two sides of said trunk line in parallel, an automatic switch in the second exchange responsive to interruptions produced in said circuit for extending a connection to a called line, means operated upon the response of the called subscriber for preventing the flow of current over said closed control circuit during conversation, and means operable from the calling end of the trunk line before the called subscriber hangs up for again setting up a current flow over said closed control circuit to release the said switch.

16. In a telephone system, two exchanges and an interconnecting trunk line, means in the first exchange for establishing a current flow over a closed switch control circuit including the two sides of said trunk line in parallel, an automatic switch in the second exchange responsive to interruptions produced in said circuit for extending a connection to a called line, means in the second exchange controlled by the called subscriber for stopping the flow of current in said closed control circuit during conversation, means in the first exchange controlled from the calling end of said trunk line for reestablishing a current flow in said closed control circuit before the called subscriber hangs up, and means in the second exchange responsive to the reestablished current flow for releasing said switch.

17. In a telephone system, two exchanges and an interconnecting trunk line, means whereby an operator in one exchange can connect with said trunk line and establish a current flow over a switch control circuit including the two sides of said trunk line in parallel, means for then momentarily interrupting the circuit at the first exchange, an automatic switch at the second exchange responsive to the interruptions for connecting with a called line, and means operated upon the response of the called subscriber for stopping the current flow in said control circuit to give the operator a supervisory signal.

18. In a telephone system, two exchanges and an interconnecting trunk line, means whereby an operator in one exchange can connect with said trunk line and establish a current flow over a switch control circuit including the two sides of said trunk line in parallel, means for then momentarily interrupting the circuit at the first exchange, an automatic switch at the second exchange responsive to the interruptions for connecting with a called line, means operated upon the response of the called subscriber for preventing the flow of current over the control circuit during conversation, and means responsive to the cessation of the current flow for giving the operator a supervisory signal.

19. In a telephone system, two exchanges

and an interconnecting trunk line, means whereby an operator in one exchange can connect with said trunk line and establish a current flow over a switch control circuit including the two sides of said trunk line in parallel, means for then momentarily interrupting the circuit at the first exchange, an automatic switch at the second exchange responsive to the interruptions for connecting with a called line, means operated upon the response of the called subscriber for stopping the current flow in said control circuit to give the operator a supervisory signal, and means operated when the operator pulls down the connection for reestablishing a flow of current in said control circuit to cause the release of said switches.

20. In a telephone system, a trunk line, a supervisory relay, means for closing a control circuit including one conductor of said trunk line and said supervisory relay in series, means for producing one or more interruptions in the circuit through said conductor, and means for closing another circuit for said relay during said interruptions to maintain the relay energized.

21. In a telephone system, a trunk line, a supervisory relay, means for closing a control circuit including one conductor of said trunk line and said supervisory relay in series, a calling device, means for placing said device in series with said conductor, and means for closing another circuit for said relay to maintain it energized while said device is being operated.

22. In a telephone system, a trunk line, a double wound supervisory relay, means for establishing a control circuit including one conductor of said trunk line and one winding of said relay in series, means for producing interruptions in said circuit, and means for closing a circuit through the other winding of said relay to maintain it energized while said interruptions are being produced.

23. In a telephone system, a trunk line, a supervisory relay, means for establishing a current flow through said relay and one conductor of said trunk line in series, means for producing an interruption in said current flow through said conductor, means for setting up a current flow through said relay over the circuit independent of said conductor to maintain said relay energized during said interruption, and other means for producing an interruption in the current flow in said conductor without closing said independent circuit to deenergize said relay.

24. In a telephone system, two exchanges, lines local to the first exchange, trunk lines extending from the second exchange, and terminating in the first exchange, connector switches, means for connecting any connector switch with any local line or any incoming trunk line, and means for then

operating said connector to connect such local line or trunk line with a desired other line.

25. In a telephone system, two exchanges, 5 two groups of non-numerical hunting switches in the first exchange, local lines terminating in the first group, trunk lines incoming from the second exchange terminating in the second group, and multiple connections between the banks of the two groups 10 and a group of connector switches.

26. In a telephone system, a trunk line terminating in a combination connector and selector switch, groups of local lines and 15 trunk lines accessible to the said switch, a

relay for changing the character of said switch from that of a connector to that of a selector when the switch is operated to select a group of trunk lines, a test wiper in said switch for testing either local or trunk 20 lines as to their busy or idle condition, a locking conductor local to said connector switch, and means for connecting said test wiper to said locking conductor when said switch is operated as a selector to connect 25 with a trunk line.

Signed by me at Chicago, Cook County, Illinois, this 7th day of October, 1920.

ARTHUR J. RAY.
